UNITED STATES PATENT OFFICE

2,325,429

JOINT BREAKER AND CATHEAD

John H. Schreiber, St. Louis, Mo.

Application July 16, 1941, Serial No. 402,661

16 Claims. (Cl. 254—173)

This invention relates to joint breakers and catheads, and is adapted and designed specially for use in oil fields and elsewhere in breaking the joints between pipe sections.

Objects of the invention are to provide an improved joint breaker and cathead having a rotor mounted for constant rotation when the device is in use and supporting a relatively movable clutch member or actuator adapted to be moved to and from an idle or unoperated position; in combination with another clutch member or shoe of novel construction and attached to the usual jerk line of the joint breaker; novel means providing a connection between said shoe and the jerk line for effectively holding the shoe in its unoperated position preparatory for engagement and movement by said first clutch member to wind the jerk line on the rotor; optional means for moving said first clutch member from its idle or unoperated position to a position in which it will engage said shoe or second clutch member during constant rotation of the rotor; and means automatically moving and disengaging said first clutch member from said shoe at the proper time, thereby permitting the jerk line to unwind itself or to be unwound from the rotor and to move said shoe to its initial or unoperated position.

Other objects of this invention are to provide an improved joint breaker and cathead having a relatively long jerk line stroke or extent of movement by and during a relatively low or slow jerk line speed of movement; to provide a drum rotative continuously in one direction when in effective operation in combination with a shoe attached to the jerk line, a device carried by and movable relative to the drum for engaging and moving the shoe in a direction to wind the jerk line on the drum, and means for releasing said device from the shoe after an effective movement of the shoe of 360° or more to wind the jerk line on the drum; to provide a removable and interchangeable insert providing the proper bore diameter and utilize this insert to hold the several parts of the unit together; to provide an improved device in which the starting speed of the jerk line is reduced to a minimum and much lower than the starting speed of jerk lines in devices now in use; and to provide a spring device for initiating the return movement of the jerk line to its starting or idle position after said device has been disengaged from the shoe.

Another object of the invention is to provide a joint breaker and cathead device composed of a minimum of units or elements including a relatively movable actuator or clutch member mounted on the rotor, and a shoe or additional clutch member attached to the usual jerk line, and means for detachably holding said elements

and thereby said clutch member and shoe in proper assembled and cooperative relationship.

Other objects will appear from the following description, reference being made to the annexed drawing, in which—

Fig. 1 is an end elevation of my improved joint breaker and cathead device and showing particularly the mechanism controlling the actuator or clutch member mounted on the rotor.

Fig. 2 is an elevation looking toward the right-hand side of Fig. 1.

Fig. 3 is a sectional view of the device transversely of the axis of the rotor.

Fig. 4 is a sectional view showing particularly the manner in which the elements of the device are held in assembled relationship, and also the manner in which the jerk line is pivotally connected with the shoe.

Fig. 5 is a transverse sectional view approximately on the line 5—5 of Fig. 2.

The present invention is embodied in a joint breaker and cathead generically of the type disclosed in my prior application Serial No. 338,559, filed June 3, 1940, now Patent No. 2,275,271, dated March 3, 1942.

The stationary frame or housing 1 is generally of annular form and is adapted to be secured rigidly to the draw-works by any appropriate attaching means. An opening 2 is provided through one side of the housing, and the jerk line 3 extends through said opening.

The rotor or drum upon which the jerk line 3 is to be wound comprises two complementary members each including an annular portion 4, an outwardly extended radial portion 5, and an inwardly extended flange 6 integral with each of said radial portions. The two annular portions 4 of the drum are in abutting contact. The drum is rotative within the frame 1 and is mounted upon and attached to a hub 6' adapted to be secured to the rotary draw-works shaft. Bolts 7 extend through formations on the hub 6' and through the annular portions 4 of the drum and through an annular wall element 8, and are provided on at least one end with removable and replaceable nuts 9 whereby the parts engaged by said bolts 7 are clamped together in rigid relationship for rotation by the draw-works shaft.

The end of the jerk line 3 within the housing 50 is rigidly attached to the abutment socket 10 the outer end of which abuts against the inner surface of the frame 1 at the opening 2 in the idle or unoperated position of the jerk line and socket. The socket 10 also functions as a link and extends between the side portions 11 of a frame-like shoe or runner mounted within the annular space 12 provided by the parts 4, 5 and 6 of the rotary drum. Said parts constitute a guide for said shoe. The side portions of the shoe are integrally connected at one end and

held in spaced relationship by a clutch portion 13 and, at a distance therefrom, are also integrally connected by a cross portion 14. The abutment socket 10 extends between the side portions 11 of the shoe and between the connecting portions 13 and 14 thereof, and is pivotally connected to said side portions by a pin 15. In the idle or unoperated position of the jerk line, the socket 10 abuts against the frame 1 at the sides of the opening 2 and holds the shoe substantially free from pressure against or frictional engagement with the rotor by the jerk line. This enables the rotor to rotate freely without affecting the shoe so that the shoe may rest or be supported in its idle or unoperated position without objectionable interference by the rotor.

An actuator or clutch member 16 is carried by and movable relative to the rotor from and to an unoperated position. In its unoperated position, the outer surface of the actuator or clutch member 16 is in continuous arcuate alignment with the periphery of that portion of the rotor provided by the portions 4 (Fig. 3). When the actuator or clutch member 16 is turned from its unoperated position to effective position, the advance edge thereof projects into the space 12 and beyond the periphery of the parts 4 of the rotor far enough to engage the clutch portion 13 of the shoe and thereby move the shoe through the space 12 from the unoperated position shown in Fig. 3 to the ultimate operated position shown in Fig. 5, and thereby wind the jerk line on the rotary drum, as shown.

One end of the actuator 16 projects through the outer wall 5 of the rotor, and a rocker arm 17 is attached to the outer end thereof. A roller 18 is supported at one side of the rear end of the arm 17, and a similar roller 19 is supported at the opposite side of the opposite end of the arm 17 so that said rollers 18 and 19 are disaligned and move in adjacent parallel paths of travel when the rotor is running. A spring actuated detent 20 mounted in the rotor is engageable in recesses 21 in the actuator 16 and is effective to hold said actuator yieldingly in the two positions to which it may be turned. This is to say that when the detent 20 is engaged in one of the recesses 21, the actuator 16 will be held in its unoperated position (Fig. 3); and, when said actuator is turned to its operated position (Fig. 5), said detent is engaged in the other recess 21.

A lever 22 is mounted on a pivot 23 supported by the frame 1 and is formed with a cam 24. The lever 22 may be held in a position to support the cam out of the way of the roller 18 so that the drum may rotate continuously without contact of the roller 18 with the cam 24. A spring 25 may yieldingly hold the lever 22 in the position in which the cam 24 will not be engaged by the roller 18. The lever 22 is optionally movable by a connection 26 to place the cam 24 in a position to be engaged by the roller 18 during rotation of the drum. When the roller 18 engages the cam 24 during rotation of the drum, the rocker arm 17 is thereby operated to turn the actuator 16 from its unoperated position (Fig. 3) to its effective or operated position (Fig. 5) in which latter position said actuator will engage the part 13 of the shoe and move said shoe around the axis of said drum along with the rotor to wind the jerk line 3 on the drum. The detent 20 yields to permit this movement of the actuator 16.

A cam 27 is formed on an arm 28 mounted on the pivot 23 and, in the unoperated position of

the jerk line 3, is held away from the frame of the cathead by a spring 29, or otherwise. When the arm 28 is held away from the frame 1 by the spring 29 or otherwise, the cam 27 is beyond and out of the path of movement of the roller 19. When the arm 28 is moved inwardly adjacent to the frame 1 of the cathead, the cam 27 is thereby moved into position to be engaged by the roller 19 and to operate the rocker arm 17 to turn the actuator 16 to its initial or unoperated position and to disengage said actuator 16 from the part 13 of the shoe and thereby leave the shoe free to be moved from its operated position (Fig. 5) to its unoperated position (Fig. 3) by the unwinding of the jerk line 3 from the drum. The jerk line 3 may be operated to its unwound position by any appropriate actuator therefor, as disclosed in my said copending application, or otherwise.

The arm 28 is operated automatically to move the cam 27 to position to be engaged by the roller 19 and thereby disengage the actuator 16 from the shoe. As shown, a block 30 is adjustably attached to the jerk line 3 so that, when the shoe is moved a predetermined distance by the actuator 16 and about the axis of the drum, which is to say, when the shoe is moved from its unoperated position (Fig. 3) to the position shown in Fig. 5, said block 30 will have moved the cam 27 to position to disengage the actuator 16 from the shoe. This leaves the jerk line 3 free to be moved longitudinally in a direction to unwind said jerk line from the drum and to move the shoe to its unoperated position in which the abutment socket 10 engages the wall of the frame 1 about the opening 2 and holds the shoe substantially free from frictional engagement with the drum. The spring 25 may connect the lever 22 with the arm 28 so as to move both to their unoperated positions in which the cams 24 and 27 are out of the paths of movement of the respective rollers 18 and 19. Movement of the lever 22 by the spring 25 may be limited by the connection 26 (Fig. 1); and movement of the arm 28 by the springs 25 and 29 may be limited by engagement of the upper end of said arm with an adjacent part of the frame 1 (Fig. 3).

An arm 31 on the hub 6 may extend adjacent to the outer side of the rocker arm 17 to prevent outward longitudinal movement or displacement of the actuator 16. When the nuts 9 are removed, the hub 6 may be moved outwardly and detached from the assembly, leaving the parts that are engaged by the bolts 7 free for detachment from each other.

In operation, the drum or rotor may rotate continuously in the direction of the arrows 32 (Figs. 1 and 3) without operating the jerk line while the actuator 16 remains in its unoperated or idle position (Fig. 3) and when the cam 24 is held out of contact with the roller 18. When it is desired to operate the jerk line 3, the lever 22 is operated to move the cam 24 into position to be engaged by the roller 18 and thereby turn the actuator 16 from its unoperated position (Fig. 3) to its operated position (Fig. 5). In its operated position, the actuator 16 will engage the part 13 of the shoe and move the shoe along with the rotor and thereby wind the jerk line on the drum, as shown in Fig. 5.

Movement of the jerk line 3 in this manner engages the block 30 against the arm 28 and moves said arm in a direction and to a position to place the cam 27 in position to be engaged by the roller 19. When the roller 19 engages the

cam 27, the actuator 16 is thereby turned about its axis and promptly disengaged from the part 13 of the shoe, leaving the jerk line 3 free to be moved in a direction unwinding the same from the drum and moving the shoe to its initial or unoperated position, as shown in Fig. 3. In the unoperated position of the shoe, the abutment socket 10 engages against the stationary frame 1 and thereby supports the shoe substantially out of frictional engagement with the rotor. The cams 24 and 27 are automatically moved out of the paths of movement of the rollers 18 and 19, respectively, by the spring 25 or otherwise, before or during unwinding of the jerk line from the drum. This leaves the parts in position for another operation when the cam 24 is moved by operation of the lever 22 to turn the actuator 16 to a position to engage the shoe.

In my improved joint breaker and cathead, the shoe that is attached to the jerk line 3 is moved at least and may be moved more than 360° about the axis of the drum before the actuator or clutch member 16 is disengaged from the shoe by the cam 27. This provides a relatively long jerk line stroke or movement which can be effected by a relatively slow jerk line speed of movement. As shown in Fig. 1, the block 30 is secured to the jerk line 3 in an adjustment to permit the minimum extent of movement of the jerk line by the rotary drum and its associated parts. This minimum movement is in excess of 360° by the distance from the line 32 to the line 33 at the periphery of the drum. This movement of the shoe more than 360° around the axis of the drum is an important and distinguishing feature of the present invention.

It should now be apparent that this invention is a highly simplified and efficient device for its intended purpose. The various elements constituting the invention may be varied as widely as the scope of equivalent limits will permit without departure from the nature and principle of the invention.

I claim:

1. In mechanism of the character described, a rotary drum having a circumferential space, and a jerk line adapted to be wound on said drum within said space; a shoe mounted in said space, an element attached to said jerk line and pivoted to said shoe for swinging movements from and to a position in which said element extends outwardly beyond the periphery of said drum, means cooperating with said element preventing substantial pressure of said shoe against said drum by said jerk line in said last named position of said element, an actuator supported by said drum for movement relative thereto into a position for engaging and positively moving said shoe and thereby said element to wind said jerk line on said drum, and devices for moving said actuator to and from said position.

2. Mechanism of the character described comprising a rotary drum, a jerk line adapted to be wound on said drum, a shoe mounted adjacent to the periphery of said drum, an element attached to said jerk line and pivotally connected with said shoe, a device carried by and movable relative to said drum for engaging and moving said shoe along with the drum in a direction to wind said jerk line on said drum, a member supported adjacent to said drum for movement to a position to move said device relative to said drum to effect a driving engagement between said device and said shoe, and means operated by said

jerk line during movement thereof by said shoe for disengaging said device from said shoe.

3. Mechanism of the character described comprising a rotary drum, a jerk line adapted to be wound on said drum, a shoe mounted adjacent to the periphery of said drum, an element pivotally connecting said jerk line with said shoe, an actuator supported by said drum for movement relative thereto into a position for engaging and positively moving said shoe along with the drum to wind said jerk line on said drum during rotation of the latter, a manually operative device for moving said actuator into said position for engaging said shoe, and means operated by said jerk line for disengaging said actuator from said shoe.

4. Mechanism of the character described comprising a rotary drum, a jerk line adapted to be wound on said drum, a shoe located adjacent to the periphery of said drum, a device pivotally connecting said jerk line with said shoe and holding said shoe free from pressure by said jerk line against said drum in the unoperated position of said shoe, an actuator mounted in said drum and movable relative thereto to engage and disengage said shoe, a manual device adjustable in a position to move said actuator to a position to engage and move said shoe along with the drum during rotation of said drum, and a device attached to said jerk line and operated thereby for disengaging said actuator from said shoe.

5. Mechanism of the character described comprising a rotary drum having a circumferential space, a jerk line adapted to be wound on said drum within said space, a shoe mounted within said space in said drum, an element pivotally connecting said jerk line with said shoe and holding said shoe substantially free from pressure by said jerk line against said drum in the unoperated position of said shoe, an actuator supported by said drum for movement relative thereto into a position for engaging and positively moving said shoe to wind said jerk line on said drum, a manual operative device for moving said actuator to said position, and means operated by said jerk line for disengaging said actuator from said shoe.

6. In a device of the character described, a drum comprising a hub adapted to be secured to a rotary shaft, a wall element, two complementary peripheral portions mounted on said hub and forming a circumferential space, detachable means engaging said hub and said wall and also engaging said two peripheral portions and holding all of said parts in rigid relationship, a shoe mounted in said space, a jerk line pivotally connected with said shoe, and an actuator mounted in said drum and movable relative thereto to engage and move said shoe along with said drum and thereby wind said jerk line on said drum within said space.

7. In a device of the character described, a drum comprising a hub adapted to be secured to a rotary shaft, a wall element, two complementary peripheral portions mounted on said hub and forming a circumferential space, detachable means engaging said hub and said wall and also engaging said two peripheral portions and holding all of said parts in rigid relationship, a shoe mounted in said space, a jerk line pivotally connected with said shoe, an actuator mounted in said drum and movable relative thereto to engage and move said shoe along with said drum and thereby wind said jerk line on said drum within said space, and means operated by said

jerk line for disengaging said actuator from said shoe.

8. Mechanism of the character described comprising a stationary housing frame, a rotary drum mounted within said frame, a jerk line adapted to be wound on said drum, a shoe located adjacent to the periphery of said drum, a device pivotally connecting said jerk line with said shoe and engaging said frame to hold said shoe free from pressure by said jerk line against said drum in the unoperated position of said shoe, and an actuator mounted in said drum and movable relative thereto to engage and move said shoe along with said drum and thereby wind said jerk line on said drum, means for disengaging said actuator from said shoe, and a device attached to said jerk line and operated thereby for moving said means to a position to disengage said actuator from said shoe.

9. Mechanism of the character described comprising a rotary drum, a jerk line adapted to be wound on said drum, a shoe located adjacent to the periphery of said drum, an element pivotally connecting said jerk line with said shoe and holding said shoe substantially free from pressure by said jerk line against said drum in the unoperated position of said shoe, means supported by and movable relative to said drum for engaging and moving said shoe along with said drum to wind said jerk line on the drum, and a device operated by said jerk line for moving said means out of engagement with said shoe after a predetermined movement of said shoe with said drum.

10. Mechanism of the character described comprising a rotary member, a jerk line adapted to be wound on said rotary member, a shoe mounted adjacent to said member and attached to said jerk line, engagement means carried by and movable relative to said rotary member for engaging and moving said shoe along with said member in a direction to wind said jerk line on said rotary member, means for moving said engagement means relative to the rotary member during rotation of the rotary member to effect a driving engagement between said engagement means and said shoe, and mechanism for moving said engagement means out of engagement with said shoe after the shoe has been moved 360° or more by the rotary member.

11. Mechanism of the character described comprising a rotary driving member for a winding surface, a stationary housing enclosing said driving member and separated therefrom by an annular space, the shoe member being mounted for movement in said annular space, a jerk line extending into said housing and having one end attached to said shoe member, a device carried by said driving member, means supported by said housing for moving said device relative to said driving member into position to engage said shoe member to effect a driving engagement between said driving member and said shoe member and to move said shoe member with said driving member and thereby wind said jerk line directly on the winding surface of said driving member, and means for moving said device to a position to release said shoe member after 360° or more of effective engagement between said device and said member.

12. Mechanism of the character described comprising a driving member, a shoe, means for supporting said shoe for movement around said

member, a line fixed at one end to said shoe and being adapted to wind on said driving member by movement of said shoe around said member, an actuator supported by and movable relative to said driving member to engage and to move said shoe around said member, an element attached to said actuator, and means for moving said element and thereby moving said actuator first to engage and then, after 360° or more of movement, to release said shoe.

13. Mechanism of the character described comprising a stationary housing, a rotary driving member extending into said housing, a jerk line, a shoe disposed between said housing and said driving member and attached to said jerk line, an actuator supported by said driving member for movement relative thereto to engage and move said shoe and wind said jerk line directly on said driving member, an element connected to said actuator for moving it relative to said rotary member to shoe engaging position, a device supported by said housing for operating said element to move said actuator to a position to engage and move said shoe, and means supported by said housing for operating said element to move said actuator to a position to disengage said actuator from said shoe after engagement therewith during 360° or more of movement of the rotary member.

14. Mechanism of the character described comprising a rotary member, a shoe member supported for sliding movement adjacent to said rotary member, a jerk line attached to said shoe to be wound thereby directly on said rotary member, an actuator supported by and movable relative to said rotary member for effecting a driving connection between said rotary and shoe members, and means movable relative to said rotary member and said actuator to effect a driving connection between said actuator and said shoe member during a full rotation of said rotary member.

15. Mechanism of the character described comprising a rotary driving member, a shoe member supported adjacent to said driving member and having a jerk line attached thereto, means for guiding said shoe member around the said driving member to wind said jerk line on said driving member, an actuator carried by and movable relative to one of said members to an engaging position for effecting a driving engagement between said members to cause the jerk line to be wound on said driving member, means for moving said actuator to and from said engaging position, means for latching said actuator either in said engaging or in a disengaging position irrespective of said driving and shoe members, and mechanism for disengaging the shoe member from the driving member after 360° of movement of said shoe member.

16. Mechanism of the character described comprising a rotary driving member, a jerk line to be wound on said driving member, means forming a shoulder on said jerk line, a device supported by said driving member for movement relative thereto to a position to engage and move said shoulder and to wind said jerk line on said driving member, and means operated by said jerk line for moving and releasing said device from said shoulder after the driving member has moved 360° or more while in engagement with said shoulder.

JOHN H. SCHREIBER.
